UNITED STATES PATENT OFFICE.

HERBERT W. WOLFF, OF ST. LOUIS, MISSOURI, ASSIGNOR TO AMERICAN CAR & FOUNDRY COMPANY, OF ST. LOUIS, MISSOURI, A CORPORATION OF NEW JERSEY.

END BRACE FOR CARS.

No. 823,837.

Specification of Letters Patent.

Patented June 19, 1906.

Application filed December 11, 1905. Serial No. 291,259.

To all whom it may concern:

Be it known that I, HERBERT W. WOLFF, a citizen of the United States, residing at St. Louis, Missouri, have invented a certain new and useful Improvement in End Braces for Cars, of which the following is a full, clear, and exact description, such as will enable others skilled in the art to which it appertains to make and use the same, reference being had to the accompanying drawings, forming part of this specification, in which—

Figure 1 is an elevational view of the end of a gondola car provided with my improved end brace. Fig. 2 is a plan view of the parts shown in Fig. 1. Fig. 3 is a sectional view on the line 3 3 of Fig. 1; and Figs. 4, 5, and 6 are views similar to Figs. 1, 2, and 3, showing a modified form of my invention.

This invention relates to the construction of cars, and particularly to that type known as "gondola" cars.

The object of my invention is to provide a car having end walls which can be subjected to great strain without liability of bulging; and to this end my invention consists in a novel end-wall brace which imparts great rigidity to said wall and also effectually ties it to the side walls of the car.

Referring to Figs. 1, 2, and 3 of the drawings, which represent the preferred form of my invention, 1 and 2 designate, respectively, the end wall and the side walls of a gondola car, said walls being provided at their upper edges with angles 3, such as cars of this type are usually provided with. Located near the center of the end wall are two vertically-extending stakes 4, which preferably are formed of channels having their respective legs of unequal length. The longer legs of said channels are connected to the end wall 1, and the shorter legs have connected thereto, by means of rivets 5, a transversely-extending brace consisting of an angle 6. The opposite ends of said angle are bent around the side walls of the car and connected thereto by rivets 7, the vertical leg of the angle being also connected to the end wall by rivets 8 and the horizontal leg being removed from the deflected portions of the angle which extend around the side walls of the car. The stakes 4 are connected to the end sill 9 by a U-shaped angle 10, having a relatively wide web portion that is fastened to the end sill by rivets 11 and provided with tapering legs 12,

which are connected to the webs of the channel-shaped stakes by means of rivets 13, thus producing a connection between the stakes and the end sill which is similar to a gusset-plate and accordingly enables said stakes to withstand great strain.

From the foregoing description it will be seen that I have provided an end-wall brace consisting practically of a truss that absolutely prevents the end wall from bulging and also securely ties said wall to the side walls of the car.

In Figs. 4, 5, and 6 I have shown a modified form of my invention in which the transversely-extending brace consists of a plate or strap 6^a, connected to the stakes 4^a and having its ends bent around the side walls of the car and connected thereto in the same manner as in the form of my invention shown in Figs. 1 to 3. In this truss the end wall of the car acts as the compression member, the brace 6 (or 6^a) as the tension member, and the central stake or stakes as the struts.

Having thus described my invention, what I claim as new, and desire to secure by Letters Patent, is—

1. A car provided with an end wall, an end stake at approximately the center of said wall, and a transversely-extending brace connected to said stake and to the opposite edge portions of the end wall; substantially as described.

2. A car comprising an end wall, side walls, an end sill, a vertically-extending stake connected to said end wall and to the end sill, and a brace extending transversely outside of the end wall of the car and connected to said stake and to the side walls; substantially as described.

3. A car comprising an end wall, side walls, a plurality of channel-shape stakes near the center of the end wall, and a transversely-extending brace having its end connected to the side walls of the car, one leg of each channel being connected to the end wall and the other leg being connected to said brace; substantially as described.

4. A car comprising an end wall, side walls and an end sill, a plurality of channel-shape stakes near the center of the end wall, a U-shape angle having its web connected to the end sill and its legs connected to the webs of the channel-shape stakes, and an angle extending transversely across the end of the

- 2
- car having its vertical leg connected to the stakes and its ends bent around the side walls of the car and connected thereto; substantially as described.
- 5 5. A car comprising side walls, an end wall and end sill, vertically-extending stakes located near the center of the end wall, a U-shape angle having a relatively wide web connected to the end sill, and tapering legs 10 which are connected to said stakes, and a transversely-extending brace connected to the stakes and to the side walls of the car; substantially as described.
- 15 6. A brace for the end of a car comprising a transversely-extending tension member located entirely at the outside of the end wall of the car and connected to said end wall thereof; substantially as described.
- 20 7. A brace for the end of a car comprising a tension member extending transversely outside the end of the car and connected to the side walls thereof; substantially as described.
- 25 8. A brace for the end of a car comprising a tension member extending transversely outside the end of the car and connected to the end and side walls thereof; substantially as described.
- 30 9. An end truss for cars consisting of a tension-brace extending transversely outside the end of the car and connected to the end and side walls thereof, and a strut coöperating with said tension-brace; substantially as described.
- 35 10. The metallic end wall of a car acting as the compression member of trussed end bracing in combination with a strut and a compression member extending transversely outside the end wall of the car; substantially as described.
- 40 11. The combination with the metallic end wall of a car which acts as a compression member of a trussed end bracing, a strut carried by said end wall, and a tension member of said bracing coöperating with said strut and said end wall; substantially as described.
- 45 12. The combination with the metallic end wall of a car which acts as a compression member of a trussed end bracing, a strut carried by said end wall, and a tension member of said bracing coöperating with said strut and said end wall, the ends of said tension member being connected to said end wall; substantially as described.
- 50 13. The combination with the metallic end wall of a car which acts as a compression member of a trussed end bracing, a strut carried by said end wall, and a tension member of said bracing coöperating with said strut and said end wall, the ends of the tension member being connected to the side wall; substantially as described.
- 55 In testimony whereof I hereunto affix my signature, in the presence of two witnesses, this 7th day of December, 1905.
- 60 HERBERT W. WOLFF.
